UNITED STATES PATENT OFFICE.

JOHN L. KEIL, OF BLAIR, NEBRASKA, ASSIGNOR OF ONE-FOURTH TO E. L. KEIL, OF SAME PEACE.

ROTARY ENGINE.

SPECIFICATION forming part of Letters Patent No. 629,297, dated July 18, 1899.

Application filed June 18, 1898. Serial No. 683,882. (No model.)

To all whom it may concern:

Be it known that I, JOHN L. KEIL, a citizen of the United States of America, residing at Blair, in the county of Washington and State 5 of Nebraska, have invented a Rotary Engine, of which the following is a specification.

The object of this invention is to economically utilize steam, compressed air, or gas in the propulsion of machinery.

10 My invention consists in the construction, arrangement, and combination of elements hereinafter set forth, pointed out in my claim, and illustrated by the accompanying drawings, in which—

15 Figure 1 is an elevation of one side of the complete engine. Fig. 2 is a vertical section of the engine. Fig. 3 is a vertical section of the engine at right angles to the section of Fig. 2.

20 In the construction of the engine as shown the numeral 10 designates a casing mounted on a base 11 and provided with removable heads 12 13. The heads 12 13 are formed with annular grooves 14 15, respectively, on their inner faces, which grooves mate with grooves 17 18, formed in the casing 10 and provided with cylinders, within which the piston-heads travel. A steam-pipe 19 is secured at one end to the central portion of a valve-chamber 25 20, located above and fixed to the casing 10, and a throttle-valve 21 is mounted for oscillation in said valve-chamber. Two ingress-ports 22 23 lead from the valve-chamber 20 to the cylinders. Rocking valves 24 25 are seated in and control the passage through the ports 22 23. A shaft 26 is mounted for rotation in the casing 10 and heads 12 13, concentric with the annular cylinders, and hubs 27 28 are mounted on and keyed to the said 30 shaft within the casing, which hubs are secured together by bolts 29 29. Packing-rings 30 30 30 30 are mounted on the hubs 27 28 and form steam-tight joints between said hubs and the casing. Piston-heads 31 32 are fixed 35 to the hubs 27 28 in diametrically opposite positions and project from the hubs into the cylinders for travel therein. Packing-rings 33 34 are mounted on the piston-heads 31 32 and form steam-tight joints between said 40 heads and the cylinders. Valve-seats are formed in the casing 10, traversing the cylinders, and sliding abutments 35 36 are mounted

for vertical reciprocation in said seats. Packing-plates 37 38 are mounted in the lower portion of the sliding abutments 35 36, and expansive springs 39 40, mounted in said sliding abutments, impinge against the plates and hold the same in contact with the hubs 27 28 when the sliding abutments are in their lowest positions. An exhaust-cavity 41 is 55 formed in the casing 10 between the cylinders, and exhaust-ports 42 42 open from the respective cylinders into said cavity, which ports are located adjacent to and on opposite sides of the vertical plane of the sliding abutments 35 36. Condensation-ports 44 45 are formed in the lower portion of the casing 10, communicating with the cylinders, and pet-cocks 46 47 control the passage through said ports. An exhaust-port 48 leads through the 60 lower portion of the casing 10 from the exhaust-cavity 41.

The throttle-valve 21 is provided with a crank 49, and a hand-lever or manually-reciprocated rod 50 is connected at one end to 75 said crank and supported on a bracket 51, fixed to the casing 10. Cranks 52 53 are fixed to the rocking valves 24 25 by means of shafts 54 55, keyed to collars 56 57, which collars carry cross-pieces 58 59, seated in notches in 80 the ends of the valves. Connecting-rods 60 61 are pivotally secured to and depend from the cranks 52 53, and the lower ends of said rods are fixed to blocks 62 63, mounted for reciprocation in oscillating levers 64 65, fulcrumed on the cylinder-head 12 by means of stub shafts or pivots 66 67. The blocks 62 63 are both connected to a connecting-rod 68 at one end, and the outer end of said rod is pivoted to the lower end of a manually-operated lever 90 69. The lever 69 is keyed near its center on one end of a rock-shaft 70, which shaft is horizontally positioned and extends from side to side of the engine. A piston 71 is mounted for reciprocation in a cylinder 72, fixed to the 95 base 11, and is connected to one end of each oscillating lever 64 65. A frame 73 is mounted on the shaft 26 for reciprocation transversely of said shaft and is connected at one end to one end of the lever 65. A cam-wheel 74 is loosely 100 mounted on the shaft 26 and is so arranged relative to the frame 73 as to reciprocate said frame. A ratchet-wheel 75, having ratchets facing both directions, is mounted on the shaft

- 26, and spring-pressed detents 76 77, oppositely arranged on the cam-wheel 74, engage the ratchets. Rocking valves 78 79 are mounted in the exhaust-ports 42 43, and gear-wheels 80 81, fixed to said valves, are engaged by rods 82 83, fixed, respectively, to the lever 69, and a crank-arm 84, fixed to the shaft 70. An oscillating lever 85 is mounted on a pivot 86, fixed to the head 12, and an antifriction-wheel 87 on one end of said lever travels in a cam-groove in a cam-wheel 88, mounted on the shaft 26. The outer end of the lever 85 is slotted, and a block 89 is mounted in the slot therein. A connecting-rod formed of two sections 90 91, telescoping relative to each other, is connected at its lower end to the block 89 and at its upper end to a crank 92, fixed to a rock-shaft 93, mounted in a bracket 94, rising from the casing 10. The section 90 and a set-screw 95 are mounted in the section through a slot 96 in the section 91. A collar 97 is rigidly mounted on the section 91, and a spring 98, of expansive character, mounted on the rod, impinges at one end against said collar. The section 90 is screw-threaded at 99, and a collar 100, interiorly screw-threaded, is mounted adjustably on the said screw-threaded portion and receives impingement of the lower end of the spring 98. The rock-shaft 93 is rigidly secured to one end of crank-arms 101 102, which extend horizontally to and are connected with stems on the sliding abutments 35 36. A slotted lever 103 is fulcrumed at its center on a pivot 104, fixed to the cylinder-head 12, and a block 105 is mounted for reciprocation in said lever. A connecting-rod 106 is fixed at its upper end to the block 105, and the lower end of said rod has a pivotal connection to the cam-wheel 88. A connecting-rod 107 is fixed at one end to the block 105 and at the other end to the lever 69 above the rock-shaft 70. The outer end of a rod 108 and the upper end of said rod is fixed to a crank 109 on a shaft 110, which shaft has a 45 bevel-gear connection with a centrifugal governor mechanism, and the governor mechanism is belted to the shaft 26. The opposite side of the engine is provided with a duplicate of the mechanism described.
- 50 In practical use the steam enters through the throttle and one of the rocking valves and engages one of the piston-heads, a backing being formed by the sliding abutment 35. The piston-head is caused to travel to the 55 point A by the steam-pressure, and at this point the steam is cut off by the automatic rotation of the rocking valve, and the expansion of the confined steam impels the piston-head to the exhaust-port, at which time the 60 expansion of the steam has entirely been utilized. When the first piston-head makes a one-half revolution, the rocking valve opens to the other cylinder, and entering steam acts upon the other piston-head in like manner.

The sliding abutments 35 36 automatically rise to permit the passage of the piston-heads after the exhaust from the respective cylinders, and the governor mechanism controls the entrance of the steam by automatically opening and closing the rocking valves. 70

By the use of the hand-lever 69 the engine may be reversed by reversing the passage of steam from one rocking valve to the other.

By arranging the exhaust near the end of the stroke I provide for utilizing the entire 75 expansive energy of the steam.

By the use of the double piston-heads I provide for the action of steam on one head or the other almost continuously, thus avoiding dead-centers and reciprocating movements. 80

It is obvious that gas, compressed air, or similar expansive medium may be employed in place of steam.

I claim as my invention—

An engine comprising a casing having two 85 or more annular cylinders, two concentric pistons mounted for travel in said cylinders, a shaft to which said concentric pistons are rigidly connected, bolts transversely seated in and rigidly connecting the hubs of the concentric pistons, steam-ingress ports leading to said cylinders, a throttle-valve arranged for manual actuation and controlling said ingress-ports, rocking valves mounted in and controlling said ports adjacent the cylinders, 95 cranks attached to said rocking valves, rods attached at their upper ends to said cranks, blocks carried on the lower ends of said rods, levers mounted for oscillation, in which said blocks are slidably mounted, dash-pot mechanism connected with the levers, a frame mounted for reciprocation and oscillation transversely of the shaft and attached to the dash-pot mechanism, a hand-lever controlling the oscillation of the frame, an adjustable 105 cam-wheel on the main shaft, a governor, connections between the cam-wheel and governor and controlled by the hand-lever controlling the oscillating levers, sliding abutments arranged for alternate rectilinear reciprocation across the cylinders, a rock-shaft, arms on said rock-shaft connected with the stems of the sliding abutments, a crank on the rock-shaft, a telescoping spring-expanded 110 pitman depending from the crank, a lever arranged for oscillation and attached at its outer end to the lower end of the pitman, the inner end of said lever engaging a groove in the cam-wheel, exhaust-ports from the cylinders, rocking valves controlling said exhaust-ports, and connections between said rocking valves and the hand-lever controlling the oscillating levers. 115 120
